Primary Examiner — Randall Gholson(74) *Attorney, Agent, or Firm* — Bentley Olive(57) **CLAIM**

I claim the ornamental design for a holder having multiple straps, as shown and described.

DESCRIPTION

This application is related to a commonly-owned U.S. utility patent application titled Holders Having Multiple, Adjustable Straps, which is being filed simultaneously herewith.

FIG. 1 is a front view of a holder having multiple straps in a disconnected state;

FIG. 2 is a rear view of the holder shown in FIG. 1;

FIG. 3 is a rear view of the holder shown in FIG. 1 while holding a pair of shoes;

FIG. 4 is a front side view of the holder shown in FIG. 1 while holding a pair of shoes;

FIG. 5 is a perspective view of the holder shown in FIG. 1 while holding a pair of shoes; and,

FIG. 6 is another perspective view of the holder shown in FIG. 1 while holding a pair of shoes.

The broken lines depict portions of the holder having multiple straps that form no part of the claimed design. The shoes shown in broken lines illustrate the environment of the claimed design and likewise form no part of the claimed design.
